GRACE E. McNAMARA, OF LOS ANGELES, CALIFORNIA

FINGER PROTECTOR

Application filed October 6, 1928. Serial No. 310,704.

This invention relates to improvements in finger tip protectors.

The general object of the invention is to provide an improved finger tip protector especially adapted for use in sorting papers, dealing cards etc., and which is especially shaped to fit the thumb or finger and is so constructed that it prevents excess perspiration when in use.

10 Other objects and the advantages of this invention will be apparent from the following description taken in connection with the accompanying drawings wherein:

Fig. 1 is a side elevation of my improved device showing it operatively positioned on a thumb.

15 Fig. 2 is an enlarged longitudinal section through the device.

Fig. 3 is a rear end view of the device.

20 Fig. 4 is a top plan view of the device and Fig. 5 is an enlarged fragmentary section of the body portion of the device.

Referring to the drawings by reference characters I have indicated my invention generally at 10. As shown the protector device includes a body portion 12 and a strap 13. It is preferably molded or cast of rubber or celluloid. The body portion 12 is formed to fit the under side of the thumb (or finger) 30 and is adapted to extend over the end of the thumb as indicated at 14 to a point adjacent the under side of the thumb nail. The rear portion of the device as indicated at 15 is adapted to extend to a point just forward of the thumb joint so that it will not interfere with the flexing of the thumb.

The strap 13 is inclined forwardly with respect to the plane of the bottom 15' of the protector and is adapted to be positioned between the thumb nail and the thumb joint as clearly shown in Fig. 1.

The outside of the body portion 12 is knurled as indicated at 16 and each section of the knurling is preferably pointed as clearly shown in Fig. 5. The body portion 12 is also preferably provided with a plurality of ventilating apertures 17 which are preferably of a frusto conical shape so that they provide a partial vacuum when pressed against a card or other object.

It will be seen that for the exception of the strap 13 the upper portion of the thumb is not covered and the apertures 17 provide ventilation thereby preventing perspiration when the device is used.

55 The device 10 may be made in various sizes to fit various sized thumbs and fingers.

My device is highly sanitary so that it is efficient not only in manipulating objects but also from the health standpoint.

60 From the foregoing description it will be apparent that I have provided an improved finger protector which is simple in construction, cheap to manufacture and highly efficient in use.

65 Having thus described my invention, I claim:

In a protector, a resilient rubber body portion, said body portion including a lower front portion shaped to engage the lower front portion of a finger from a point adjacent to the underside of the finger nail rearwardly, a lower rear portion adapted to engage the lower rear portion of the first joint of the finger, an intermediate bottom portion between the portions, said rear portion being normally upwardly inclined from the intermediate bottom portion and means to hold the protector on a finger.

70 In testimony whereof, I hereunto affix my signature.

75 GRACE E. McNAMARA.
